UNITED STATES PATENT OFFICE

102,734

DESIGN FOR A TYPEWRITING MACHINE

John A. Zellers, Bronxville, and Herbert E. Bridgwater, Syracuse, N. Y., assignors to Remington Rand Inc., Buffalo, N. Y., a corporation of Delaware

Application December 6, 1935, Serial No. 59,945

Term of patent 7 years

To all whom it may concern:

Be it known that we, John A. Zellers and Herbert E. Bridgwater, citizens of the United States, residing respectively at Bronxville, in the county of Westchester and State of New York, and Syracuse, in the county of Onondaga and State of New York, have jointly invented a new, original, and ornamental Design for Typewriting Machines, of which the following is a specification, reference being had to the accompanying drawing, forming a part thereof.

Fig. 1 is a perspective view of a typewriting machine showing our design.

Fig. 2 is an end view of the same.

The characteristic feature of the design re-

sides in the convexly curved cover plate *a* as shown, terminating at its front and side lower edges in a horizontally disposed bead *b* which surrounds the cover plate on three sides, the front central portion of the cover plate extending upwardly from the substantially straight bead *b* in a slightly outwardly curved line *c* to the bead *d*, forming the rear curved edge upper plate at its upper terminus.

We claim:

The ornamental design for a typewriting machine, as shown and described.

JOHN A. ZELLERS.
HERBERT E. BRIDGWATER.
